COMBINED SUNGLASSES AND HAIR BAND

Atherton Mitchell, San Francisco, Calif., assignor to Renauld International, Inc., Reading, Pa., a corporation of Pennsylvania

Filed Aug. 13, 1964, Ser. No. 81,268

Term of patent 14 years

(Cl. D57—1)

FIG. 1 is a front perspective view of combined sunglasses and hair band showing my new design;

FIG. 2 is a side elevational view; and

FIG. 3 is a rear perspective view.

I claim:

The ornamental design for combined sunglasses and hair band, substantially as shown.
